UNITED STATES PATENT OFFICE

JULIEN J. FROSKAUER, OF NEW YORK, N. Y., ASSIGNOR TO WILLIAM C. POPPER AND COMPANY, OF NEW YORK, N. Y.

COMBINATION PRICE TAG AND INSTRUCTION BOOK

Application filed August 16, 1928. Serial No. 299,997.

This invention relates to improvements in price tags or other marking or identification means.

An object of the invention comprehends a flap portion adapted to be folded against the tag proper.

Another object of the invention contemplates a booklet held between the flap and tag and upon which may be written the instructions for the use and proper care of the article identified.

With the above and other objects in view, the invention further consists in the following novel features and details of construction, to be hereinafter more fully described, illustrated in the accompanying drawings and pointed out in the appended claim.

In the drawings:—

Figures 1 and 2 are front and rear elevations of the present invention.

Figure 3 is an elevation of the invention with the flap disengaged and extended from the tag proper.

Figure 4 is a longitudinal sectional view taken on line 4—4 of Figure 3.

Referring to the drawings in detail, wherein like characters of reference denote corresponding parts, the reference character 10 indicates a price tag having an extension or flap 11 projecting from a line of scoring 12 horizontally disposed with relation to the tag.

The flap or extension is adapted to be folded upon the line of scoring 12 to dispose an opening 13 adjacent the end thereof in registration with an opening 14 within the uppermost end of the tag 10 to permit insertion of a cord or other tie, such as indicated at 15.

A book of instructions, as generally indicated at 16, and comprising leaves 17, are adapted to be joined adjacent the uppermost ends thereof to the tag 10 upon the opposite sides of the opening 14 therein through the instrumentality of staples 18. The tie 15 is also passed through the upper portions of the leaves 17.

The instructions upon the leaves 17 will inform the purchaser of the article just what the article is, its use, and care required to facilitate the desired performance.

50 The outer surfaces of both the tag and flap

therefore may be employed to exhibit the name of the product, the model, type, catalogue number, price, size, address of the manufacturer, address of the retailer, a notice that instructions for the use and proper care of 55 the article are included within the pocket defined between the tag and flap, etc. The present price tag in general use is only adequate for a description and price of the object to which it is attached. Many manufacturers 60 have to use, in conjunction with this tag, an extra instruction book or catalogue, describing their products. With the improved price tag and instruction book combination, the two, namely, the tag and catalogue, are 65 included in one. The advantages of the present invention are particularly noticeable when one considers that the average retail salesman knows nothing of the article being sold.

70 It is a simple matter with the improved price tag and instruction book combination for the sales person looking at the tag on the object, to undo the string or tie and read the booklet enclosed in the tag, thus familiarizing himself with the product he is selling.

75 For the consumer, this new combination insures the instruction book reaching him intact with the tag. Separate instruction books, as a rule, are lost, and the present invention prevents the object being sold reaching its destination without proper instructions for its operation.

Catalogues, describing other products than the one sold, can also be advertised in the same 85 booklet.

The invention is susceptible of various changes in its form, proportions and minor details of construction, and the right is herein reserved to make such changes as properly fall within the scope of the appended claim.

Having thus described the invention, what is claimed is:—

90 The combination of a price tag having a flap projecting from one end thereof, leaves in booklet form carried upon the inner face and extending throughout the length of the tag, said flap having folding connection with one end of the tag along a horizontal line of scoring below the unbound ends of the leaves 100

for a distance equal to the thickness of the booklet to prevent bulging of the tag and flap, about the booklet of leaves, and a package tie establishing detachable connection between the adjacent ends of the tag and flap through the bound edges of the booklet.

5 In testimony whereof I affix my signature.
JULIEN J. PROSKAUER.
